UNITED STATES PATENT OFFICE.

WILLIAM N. SPRINGER, OF PEORIA, ILLINOIS, ASSIGNOR TO AVERY COMPANY, A CORPORATION OF ILLINOIS.

FIRE-DOOR FOR FURNACES.

1,066,670.

Specification of Letters Patent.

Patented July 8, 1913.

Application filed June 1, 1909. Serial No. 499,454.

To all whom it may concern:

Be it known that I, WILLIAM N. SPRINGER, a citizen of the United States, residing at Peoria, in the county of Peoria and State of Illinois, have invented certain new and useful Improvements in Fire-Doors for Furnaces, of which the following is a specification, reference being had therein to the accompanying drawing.

10. This invention relates to fire doors for furnaces and in particular to those adapted and intended for use on the furnaces of traction engines or locomotives. It will be understood, however, that a fire-door embodying my invention is equally applicable to any other furnace into which it is desirable to feed fuel by means of a shovel.

15. The principal object of the invention is to produce a door of the type specified which may be quickly and readily opened by means of a lever within reach of the fireman's foot.

20. My invention further relates to various details of construction and arrangements of parts which will be fully set forth in the following specification.

25. Of the drawings—Figure 1 is a fragmentary view showing the rear part of a traction engine with a door embodying my invention attached. Fig. 2 is a cross sectional view through the door and the frame. The dotted lines show the door in the open position. Fig. 3 is an elevation. Fig. 4 is a cross sectional view through the frame and one set of bearings, the corresponding door section being shown in elevation. Fig. 5 is a detail view of one of the gear wheels.

30. Referring to the drawings, 1 represents the frame of the door. This frame is adapted to be attached to the fire-box of a boiler or to any other suitable furnace by means of bolts passing through the holes 2.

35. 3 and 3^a are the sections of the door proper and are provided with the lugs 4, 4 which carry the tapered trunnions 5, 5.

40. 6, 6 are bearing brackets which are bolted to the frame and which have tapered bearings 7, 7 for the trunnions 5, 5.

45. The outer ends of the trunnions are preferably square in cross section. Gears 8 and 8' are mounted upon the square ends of the trunnions at one end of the door sections and mesh with each other. They are fastened in place by the cotter pins 9. Each of the gears 8 and 8' is formed of two sections 8^a and 8^b which are secured together

by the through bolts 8^c which pass through slots 8^d in the inner section 8^b. By loosening the nuts on the bolts the section 8^a may be adjusted relatively to the section 8^b.

50. Each of the door sections 3 and 3^a is provided with a plate 10 which is attached by means of the bolts 11. Each of these plates is in the form of a section of a cylinder having its axis passing through the axis of the corresponding trunnions 5, 5. The plates are 55 intended to protect the door sections from the injurious effect of the heat and of the products of combustion. These plates may be renewed from time to time, whenever such renewal is necessary. The door section 70 3 is provided with a lip 12 which is formed to engage the frame 1 and limit the motion of the door section. The section 3^a is provided with a similar lip 13. The section 3^a is also provided with a lip 14 which is 75 adapted to overlap the section 3, and thus form a comparatively tight joint between the two.

75. 15 is a pitman pivotally attached at its upper end to the gear 8 in such a way that 80 the downward movement of the pitman will rotate the gears to open the door sections. The lower end of the pitman is attached to a foot-lever 16 which is pivotally mounted at 85 one end and provided with a spring 17 which tends to lift the lever.

90. The operation of the device is as follows: The inner and outer parts of the gears 8 and 8' are first adjusted so that the door sections may be moved into the closed position shown by the full lines of Fig. 2. The corresponding positions of the gears and the operating mechanism is shown in Fig. 1. When it is desired to open the doors to throw in a shovelful of coal, the fireman 95 depresses with his foot the lever 16. By means of the pitman 15, the gears 8 and 8' are rotated, carrying with them the door sections which assume the positions indicated by the dotted lines of Fig. 2. As soon as the fireman releases the lever 16, the spring 17 lifts it and the operation above described is reversed and door sections are brought to their closed position.

100. It will be understood that I do not desire to limit myself to the exact details herein shown and described, as many changes in the details may be made within the scope of my invention. For instance, it is not necessary to use the complete gears which have 110

been shown, for as the gears rotate through an angle of somewhat less than ninety degrees, fragmentary gears or quadrants would be found sufficient to operate the door sections. The foot operating mechanism, which I have shown and described is the one which I at present prefer but other suitable mechanism may be used for actuating the gears.

10 The advantages of a fire door embodying my invention will be readily apparent to those familiar with the construction and operation of furnaces and boilers. With the simple swing doors which are at present 15 commonly used it is necessary for the fireman to open the door before picking up a shovelful of coal. This necessitates the door being open for a considerable time with a consequent loss of heat by radiation. A 20 considerable amount of cold air goes into the furnace and this tends not only to deaden the fire but also in time to bring the boiler into a leaky condition because of the consequent contraction and expansion of the 25 flues. All of these difficulties and disadvantages are obviated by the use of my improved door. A still further advantage incident to my improved door is that the fireman is more fully protected from the heat 30 of the fire and is enabled to do his work more comfortably and more satisfactorily. Another advantage in the construction which I employ is that it is entirely counterbalanced. The section 3 is moving downward at the same time that the section 3^a is moving upward, and therefore the only force required is that necessary to overcome 35 the friction and the tension of the spring 17. I am aware that various forms of doors 40 have been proposed which may be operated by a foot or hand lever or by power, and I do not, therefore, claim broadly a door so operated.

What I claim is:

45 1. In a boiler furnace door, the combination of a vertical door frame, two parallel pairs of aligned bearings mounted on the frame in a remote plane parallel to and on the outer side of the plane of the said 50 frame, two door sections normally positioned adjacent one another at the outer side of the door frame to close the opening therethrough, a pair of trunnions on one door section mounted in one pair of the said 55 aligned bearings, a second pair of trunnions on the other door section mounted in the other pair of aligned bearings, gearing between the door sections for causing the movement of one of the sections upward 60 about its trunnion axis along a path between the said axis and the frame simultaneously with the movement of the other section downward about its trunnion axis along a path between the said axis and the 65 frame, whereby counterbalancing is effect-

ed, and means for moving the doors, substantially as set forth.

2. In a furnace door, a door frame, and door sections adapted to normally close the door opening and to swing oppositely about pivotal points in a plane on the outer side of the plane of the said door frame, each door section comprising a main outer plate and a removable inner plate having a curved surface concentric with the pivotal axis of the door, substantially as set forth. 70

3. In a furnace door, two parallel door sections, each provided with two pivotal trunnions in alignment with each other outside of the plane of the section and substantially midway between its edges, a door frame provided with outwardly extending bearings one for each trunnion, and two intermeshing gears one mounted on a trunnion of one section and the other on the corresponding trunnion of the other section, one of said gears being adjustable angularly about the said trunnion axis, substantially as set forth. 80

4. In a furnace door, two parallel door sections, each provided with two pivotal trunnions in alignment with each other outside of the plane of the section and substantially midway between its edges, a door frame provided with outwardly extending bearings one for each trunnion, two intermeshing gears one mounted on a trunnion of one section and the other on the corresponding trunnion of the other section, one of said gears being adjustable angularly about the said trunnion axis, and mechanism for rotating said gears to open or close the said door sections, substantially as set forth. 90

5. In a furnace door, two parallel door sections, each provided with two pivotal trunnions in alignment with each other outside of the plane of the section and substantially midway between its edges, a door frame provided with outwardly extending bearings one for each trunnion, two intermeshing gears one mounted on a trunnion of one section and the other on the corresponding trunnion of the other section, one of said gears being adjustable angularly about the said trunnion axis, mechanism for rotating said gears to open said door sections, and means for automatically closing said door sections, substantially as set forth. 105

6. In a furnace door, a door frame, two door sections normally positioned adjacent one another at the outer side of the door frame to close the opening therethrough, means for pivotally mounting the sections to swing away from each other, about points in a plane outside the plane of the sections, means for connecting the sections to insure 120 their simultaneous movement in opposite directions, a lip on one of the adjacent edges of the sections to overlap the other edge when the sections are in normal position, and a lip at each of the non-adjacent edges 130

of the door sections, each lip lying at an angle to the plane of the corresponding section and adapted to engage the door frame, substantially as set forth.

- 5 7. In a door, a frame, bearing brackets, one at each end of the frame, each bracket being provided with two bearing apertures, two door sections each provided with two trunnions in alignment with each other and
10 located in a line outside of and parallel to the plane of the door section, and similarly placed relative to its edges, and each adapted to fit into and turn in the bearing apertures of the brackets, lips on the door sections whereby they may engage the frame to

limit their motion and make an overlapping joint therewith, a lip on one of the sections which overlaps the other section when they are in the closed position, intermeshing gears upon the trunnions at one end of each door section, and means for rotating one of the gears to move the door sections, substantially as set forth. 20

In testimony whereof I affix my signature, in presence of two witnesses.

WILLIAM N. SPRINGER.
